US00D851667S

(12) **United States Design Patent** (10) Patent No.: **US D851,667 S**
Watson (45) Date of Patent: **** Jun. 18, 2019**

(54) **DISPLAY SCREEN WITH GRAPHICAL USER INTERFACE FOR ASSESSMENT INSTRUCTIONS**

(71) Applicant: **HUMANTELLIGENCE INC**, Miami Beach, FL (US)

(72) Inventor: **Russell J. Watson**, New Berlin, WI (US)

(73) Assignee: **HUMANTELLIGENCE INC.**, Miami Beach, FL (US)

(**) Term: **15 Years**

(21) Appl. No.: **29/619,476**

(22) Filed: **Sep. 29, 2017**

(51) LOC (11) Cl. **14-04**

(52) U.S. Cl.

USPC **D14/486**

(58) **Field of Classification Search**

(57) **CLAIM**

The ornamental design for a display screen with graphical user interface for assessment instructions, as shown and described.

DESCRIPTION

The file of this patent application contains at least one drawing/photograph executed in color. Copies of this patent with color drawing(s)/photograph(s) will be provided by the Office upon request and payment of the necessary fee.

The sole FIGURE is a front view of a display screen with graphical user interface for assessment instructions.

The broken line showing of a display screen is included for the purpose of showing portions of the article which form no part of the claim. The broken line showing of environmental structure forms no part of the claimed design.

**1 Claim, 1 Drawing Sheet
(1 of 1 Drawing Sheet(s) Filed in Color)**
